TOBACCO LEAF HANGER

Jack Hays, Tompkinsville, Ky., assignor of one-half to James C. Carter, Jr., Tompkinsville, Ky.

Application September 19, 1941, Serial No. 411,563

5 Claims. (Cl. 294—5.5)

The present invention relates to new and useful improvements in tobacco leaf hangers and has for its primary object to provide, in a manner as hereinafter set forth, a device of this character which is adapted to be expeditiously mounted on either or both sides of a tobacco stick and which includes novel means for receiving and securely holding the bottom leaves which have been removed from the stalks.

Other objects of the invention are to provide a tobacco leaf hanger of the aforementioned character which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference 20 designate corresponding parts throughout the several views, and wherein:

Figure 1 is an elevational view of the invention.

Figure 2 is a top plan view thereof.

Figure 3 is a cross sectional view, taken substantially on the line 3—3 of Figure 1.

Figure 4 is a cross sectional view, taken substantially on the line 4—4 of Figure 1.

Figure 5 is a view in front elevation of an end portion of another form of the invention.

Figure 6 is a plan view thereof.

Referring now to the drawings in detail, it will be seen that reference numeral 1 designates a rod of suitable metal, which rod may be of any desired length. The rod 1 is secured longitudinally on a tobacco stick 2 through the medium of staples 3.

Mounted longitudinally at spaced points on the rod 1 is a series of angular resilient clips 4. The 40 clips 4 terminate in upturned free end portions 5.

Also fixed, as by welding or soldering, at spaced points on the rod 1 are crossheads 6. The crossheads 6 are adapted to bear against the stick 2 in a manner to positively prevent rotation of the rod 1 in the staples 3.

The resilient clips 4 coat with the rod 1 for firmly gripping and retaining the stems 7 of the bottom tobacco leaves 8. Thus, these valuable leaves are suspended for curing in a manner to prevent them from sustaining injury. The upturned free end portions 5 facilitate springing the resilient clips 4 outwardly for the insertion of the leaf stems 7. In the drawing a leaf hanger in accordance with the present invention is shown on both sides of the stick 2. Of course, if desired, a single device may be used on only one side of the stick.

In Figures 5 and 6 of the drawings reference numeral 9 designates a bar of suitable resilient 60

sheet metal. Struck from one of the longitudinal marginal portions of the bar 9 is a series of spaced, angular resilient clips 10. The clips 10 terminate in outturned free end portions 11 which facilitate the insertion of the stems of the tobacco leaves beneath said clips. The bar 9 may be mounted on a suitable supporting means and the clips 10 coat with said bar for gripping and retaining the leaf stems.

It is believed that the many advantages of a tobacco leaf hanger constructed in accordance with the present invention will be readily understood and although preferred embodiments of the device are as illustrated and described, it is to be understood that further modifications and changes in the details of construction may be resorted to which will fall within the scope of the invention as claimed.

What is claimed is:

1. A tobacco leaf hanger of the character described comprising an elongated horizontal metallic member, and a series of spaced, angular resilient clips on top of said member and extending substantially parallel therewith, said clips being operable across the member and cooperable therewith for receiving and frictionally gripping the stems of tobacco leaves, said clips including angularly extending free end portions.

2. A tobacco leaf hanger comprising a horizontal stick, a rod mounted longitudinally on said stick, and a series of spaced, angular resilient clips mounted longitudinally on said rod and cooperable therewith for gripping and frictionally retaining the stems of tobacco leaves, said clips including vertical free end portions extending in opposed relation to the stick.

3. A tobacco leaf hanger comprising a rod for mounting on a stick, crossheads mounted on said rod and engageable with the stick for preventing rotation of said rod thereon, and a plurality of resilient clips mounted on the rod.

4. A tobacco leaf hanger of the character described comprising a metallic rod of circular cross-section, means for securing said rod on a stick, a plurality of crossheads mounted at spaced points on the rod and engageable with the stick for preventing rotation of said rod thereon, and a series of spaced, angular resilient clips mounted longitudinally on the rod and cooperable therewith for receiving and frictionally gripping the stems of tobacco leaves, said clips including upturned free end portions.

5. A tobacco leaf hanger comprising a bar of resilient sheet metal, and a series of longitudinally spaced, resilient clips struck from one of the longitudinal marginal portions of the bar and cooperable therewith for receiving and frictionally gripping the stems of tobacco leaves.

JACK HAYS.
